UNITED STATES PATENT OFFICE.

ANNA KUSZMINK, OF POSEN, GERMANY.

SPLINTER-BAR FOR VEHICLES.

SPECIFICATION forming part of Letters Patent No. 693,405, dated February 18, 1902.

Application filed June 25, 1900. Serial No. 21,586. (No model.)

To all whom it may concern:

Be it known that I, ANNA KUSZMINK, a subject of the King of Prussia, German Emperor, residing at 19 Victoriastrasse, Posen, in the 5 Kingdom of Prussia, German Empire, have invented new and useful Improvements Relating to Splinter-Bars for Vehicles; and I do hereby declare that the following is a full and clear description thereof.

10 This invention relates to splinter-bars for vehicles, and comprises a device by means of which the traces may be released instantaneously.

15 The improved device comprises a draw-rod having an enlarged head normally held firmly by two revolving holders or catches, which on being turned around release the head, so that the horses will be freed.

20 In the accompanying drawings, illustrating the invention, Figure 1 shows a plan of the splinter-bar. Fig. 2 is a section through the same. Fig. 3 represents the closed coupling device in vertical longitudinal section. Fig. 4 is a horizontal longitudinal section of the 25 same. Fig. 5 shows the open coupling device with the cover-plate removed.

Upon each end of the splinter-bar *a* is fitted a coupling, as shown separately in Figs. 3 to 5. A case *b* incloses two holders or catches *c*, 30 to one of which an arm *d* is connected, the holders or catches *c* being coupled together by toothed wheels *e*, so that both holders or catches will be revolved simultaneously when the arm *d* is turned by the strap or rod *f* through the intervention of the lever *g* on the shaft *h*, the arms *i* on such shaft, and the links *k*.

The holders or catches *c* consist of cylinders from which a portion has been cut away 40 on one side, so that in their closed position they will hold between them a draw-rod *m*, presenting an enlarged head *n* and connected with the end of the trace, and in order that

the latter may take any position the connection is made by links, forming a universal 45 joint. As shown in Fig. 3, the holders or catches *c* in the closed position firmly hold the heads *n* of the draw-rod *m*, but release it as soon as the strap or rod *f* is pulled. The holders or catches then occupy the position 50 shown in Fig. 5. Inside the case *b* is a plate *p*, adapted to be pressed outward by a spring. As the head *n* is pressed against the holders or catches *c* the projections *q* in the case *b* furnish a guide for such head *n*, while a 55 spring *r* keeps the holders or catches in their closed position, Fig. 3. By the arrangement described the more the draw-rod *m* is pulled the more firmly it will be held by the holders or catches *c*, thus rendering accidental uncoupling impossible.

Having thus described my invention, what I claim, and desire to secure by Letters Patent, is—

1. In vehicles, a splinter-bar provided with 65 cases carrying revoluble holders having intermeshing toothed wheels, a rod passing between said holders and terminating in an enlarged head, and means for revolving said holders whereby the rod may be released, all 70 arranged as set forth.

2. In vehicles a splinter-bar provided with cases carrying revoluble holders, a rod passing between said holders and terminating in an enlarged head a spring-actuated plate 75 pressing said head in contact with the holders, and means for revolving said holders whereby the rod will be released, all combined as set forth.

In testimony that I claim the foregoing I 80 have hereunto set my hand in the presence of two witnesses.

ANNA KUSZMINK.

Witnesses:

HERMANN BARTSCH,
ALBERT SCHENK.
